Patented July 12, 1921.

FIG. 1.

FIG. 2.

FIG. 3.

Inventor
Joseph F. Maloney.
by Herbert W. Jenner.
Attorney

UNITED STATES PATENT OFFICE.

JOSEPH FRANCIS MALONEY, OF CLEVELAND, OHIO.

AIR-MOISTENER.

1,384,702.

Specification of Letters Patent. Patented July 12, 1921.

Application filed September 11, 1919. Serial No. 323,059.

To all whom it may concern:

Be it known that I, JOSEPH F. MALONEY, a citizen of the United States, residing at Cleveland, in the county of Cuyahoga and State of Ohio, have invented certain new and useful Improvements in Air-Moisteners, of which the following is a specification.

This invention relates to devices for supplying aqueous vapor to mix with the combustible charges of internal combustion engines; and it consists in the novel construction and combination of the parts herein-after fully described and claimed.

In the drawings, Figure 1 is a side view 15 of an internal combustion engine and a radiator, partly in section, showing moistening devices constructed according to this invention. Fig. 2 is a sectional plan view of the hot air funnel. Fig. 3 is a detail view 20 in section of the cold air regulator.

The engine 2 is provided with an intake manifold 3 and an exhaust manifold 4 of any approved construction. A radiator 5 such as ordinarily used on motor cars is arranged at the front end of the engine, and has a space 6 for aqueous vapor above its water space. A fan 7 of approved construction is interposed between the engine and the radiator, and discharges air rearwardly 25 as indicated by the arrows in Fig. 1.

A funnel 8 for air and aqueous vapor is arranged on top of the exhaust manifold 4, and is secured in position by any approved fastening devices or clamps 10. The 35 larger end of the funnel projects forwardly of the exhaust manifold, and receives the air from the fan, which is revolved by the engine. The smaller end of the funnel is connected to the carbureter 12, which is of any approved construction, by means of a 40 flexible tube 14. The carbureter is connected to the intake manifold, and a regulator 13 is arranged to connect it with the flexible pipe 14. The regulator is tubular, 45 and it has lateral holes or openings 16 for the admission of cold air to the carbureter, and 17 is a cylindrical slide on the regulator which is slid back and forth to vary the size of the air passage through the said 50 holes or openings, or to close it altogether.

The funnel has holes or slots 18 in its underside for the admission of hot air from the top surface of the exhaust manifold.

A flexible pipe 20 is provided, and one end portion of it is connected by a tubular stem 55 21 with the vapor space 6 at the top of the radiator.

The other end portion of the flexible vapor pipe 20 is secured in a lug or loop 22 inside the funnel at its larger end, and 60 24 is a drain hole for water under the outlet end of the pipe 20. The drain hole is formed in the funnel so that no water which drips from the pipe 20 may find its way 65 into the carbureter. The funnel is conical from end to end, and is preferably circular in cross-section, but it is not necessarily circular. The hot air inlet extends longitudinally along its bottom side, and its bottom side is inclined downwardly toward the 70 drain hole 24. The flexible pipe 14 is connected axially to the smaller end of the funnel, and the larger end of the funnel is made relatively very large, so that the blast 75 of air from the fan may force the mixed hot air and vapor through the funnel and down the pipe 14. Flexible pipes are provided so that the various parts can be readily assembled together and applied to different makes of engines and motor cars. 80

The aqueous vapor thus introduced into the carbureter has a beneficial effect in the engine cylinders, by decreasing the deposits of carbon, and in other ways.

What I claim is:

The combination, with an internal combustion engine provided with a fan, and a radiator arranged in front of the fan; of a tubular funnel adapted to receive a blast of air from the fan, said funnel having its 90 lower side inclined downwardly and forwardly and provided with an inlet for hot air arising from the engine, a pipe for vapor communicating with the vapor space of the radiator, a fastening device securing the open rear end of the vapor pipe to the lower inclined side of the funnel at its front end so that condensed vapor may drip from the front end of the funnel, and a 95 delivery pipe for moistened and heated air 100 secured to the rear end of the funnel in line with its axis and operatively connected with the fuel intake of the engine.

In testimony whereof I have affixed my signature.

JOSEPH FRANCIS MALONEY.
